REFRIGERATOR SYSTEM FOR PRODUCE STANDS

Harry Y. Stebbins, Los Angeles, Calif., assignor to
General American Transportation Corporation,
Chicago, Ill., a corporation of New York

Application October 8, 1949, Serial No. 120,325

6 Claims. (Cl. 62—89.5)

1

This invention relates to refrigerated display racks of the open top variety and has for its principal object the provision of a new and improved device of this kind.

It is a main object of the invention to provide a refrigerated open top display rack capable of fitting in the same space as the prior art non-refrigerated racks.

Another object of the invention is to provide a refrigerating apparatus capable of being fitted into existing display racks.

Another object of the invention is to provide a refrigerating apparatus for display racks that is capable of being readily altered to vary the dimensions of the several bins formed in the rack.

Another object of the invention is to provide a refrigerating apparatus for open top display racks which can be manufactured at low cost without sacrificing quality, and which can be maintained clean and sanitary economically.

Further objects of the invention not specifically mentioned here will be apparent from the detailed description and claims which follow, reference being had to the accompanying drawings in which a preferred embodiment of the invention is shown by way of example and in which:

Fig. 1 is a plan view of a refrigerating apparatus installed in a display rack of typical proportions;

Fig. 2 is an end elevational view of the rack shown in Fig. 1 with the compressor condenser unit diagrammatically illustrated;

Fig. 3 is a fragmentary cross-sectional view taken substantially along the line 3—3 of Fig. 1 looking in the direction of the arrows; and

Fig. 4 is a fragmentary cross-sectional view taken substantially along the line 4—4 of Fig. 1 looking in the direction of the arrows.

Open top display racks of approximately counter height are frequently employed to display merchandise such as fruits and vegetables. Oftentimes such racks are generally rectangular having widths of approximately three feet, and lengths of ten or twelve feet or more depending upon the space available. Such box-like racks are supported upon suitable supports with the bottom of the rack inclined slightly so that the rear edge of the rack is several inches higher than the front edge. The rack is usually divided into a plurality of generally rectangular bins in which products of various kinds are displayed for sale. Oftentimes mirrors extend upwardly from the rear edge of the rack at such an angle as to enhance the appearance of the display. It is to such a rack that the instant invention relates.

2

As is well understood by those skilled in the art fruits and vegetables will remain in a better and consequently saleable condition for a longer period of time if they are maintained under refrigeration. In the prior art of which I am aware numerous efforts have been made to apply refrigeration to uses of this kind, certain of these endeavors resulting in a closed case refrigerated and maintained at proper temperature with the aid of doors or lids that serve to confine the cooled air in close proximity to the produce. Such devices, while they may improve the keeping quality of the fruits and vegetables, largely defeat their own purpose by inducing customer resistance, it being well understood that in self-service stores customers are reluctant to open refrigerator doors and the like to secure the merchandise.

In other instances in the prior art of which I am aware, the refrigerated display rack constitutes a complete new unit oftentimes differing in dimensions from the racks commonly used and, as a result, the expense of change-over from a non-refrigerated to a refrigerated rack has been so great as to greatly limit the use of the improved device.

The present invention seeks to provide a refrigerated open top display rack which can be made to precisely the same dimensions as racks now in use, the refrigerating unit of which racks if desired can be installed in existing non-refrigerated racks with a minimum of expense.

To this end and in accordance with the teachings of the present invention the refrigerating units and supports therefor form the partitions by which the rack is divided into a plurality of independent generally rectangular open top bins or compartments. The pipes forming the coils through which the heat exchange medium is circulated are supported in support members disposed at right angles to the pipe and extending from edge to edge of the rack. Usually the pipes will extend longitudinally of the rack and the supports from side to side thereof, however, if desired, the relative positions may be changed.

The supports are not secured to the pipes but rather are capable of sliding freely therealong, and the pipe sections intervening between adjacent supports are covered by planar members tightly embracing the pipes and abutting against the supports to space the supports longitudinally of the pipe and to form side walls for the compartment. The supports, being movable, permit adjustment of the length of the individual compartments, the width of which compartment is

preferably more or less permanent in a particular installation. Spacing members such as are used to cover the pipe can be provided in several lengths in a particular rack, thereby forming compartments of different sizes and by interchanging these members and making corresponding adjustment of the supporting members smaller and larger bins can be repositioned in the rack as desired.

Referring now to the drawings in more detail, particularly Figs. 1 and 2, it will be seen that the rack of the type to which the present invention relates consists of a bottom plate 1 from opposite sides of which generally vertical walls 2 and 3 extend being joined at the ends of the base plate by end walls 4 and 5 respectively. The bottom plate 1 is preferably composed of metal or, if of wood, provided with a metal upper facing. The box-like structure so formed is supported upon a suitable base 6, the details of which form no part of the present invention, this support 6 supporting the base plate at an angle with respect to the horizontal which angle approximates 15° thereby to elevate the rear side 3 of the rack somewhat above the front 2. Frequently along the front edge 2 of the rack is a glass front panel 7 in which are display cards giving the price and other pertinent data relative to the contents of the bins. Extending upwardly from the rear side 3 of the rack may be a mirror 8 along the upper side of which is a suitably shaded source of light 9 by which the contents of the rack are illuminated. The rack just described will be recognized as a more or less standard fruit and vegetable display rack now commonly used in chain stores and the like.

As will be seen in Figs. 1-4 inclusive the box-like rack is divided into generally rectangular pockets by the refrigerating apparatus of the present invention, such apparatus consisting of a plurality of pipes arranged in vertical rows 10, 11, 12 and 13, which rows are shown to extend from end to end of the rack. Cross connecting pipes 14 and 15 connect the individual pipes together to form a coil through which a refrigerating medium may enter through pipe 16 and flow through the bottom ones of the pipes in each of the rows, thence to the next pipes and so on leaving the coil through the pipe 17. As shown each of the pipe rows 10, 11, 12 and 13 contains four individual pipes located one above the other; this arrangement being subject to variation within the teachings of the invention.

The pipes thus forming the refrigerating coil are supported by suitable supports 20 which are preferably generally U-shaped members that extend between and abut against the sides 2 and 3 of the rack. These U-shaped members, preferably formed of metal, contain rows of perforations 21 through which the pipes project. The members 20 are disposed with the open end of the U downward and flanges 22 are extended outwardly and rest upon the bottom or base plane 1 of the rack to support the pipes thereabove.

The holes 21 are of such dimension that the supports 20 may be moved longitudinally of the pipes without difficulty.

Fitting between adjacent supports 20 and over each row of pipes therebetween, such as for example row 11, is a spacer 25 composed of metal and of generally U-shaped section. This spacer 25 is of such dimension as to snugly fit over and engage the pipes in the row as shown in Fig. 3. The ends of the spacer 25 abut against adjacent ones of the supports 20, thereby fixing those sup-

ports longitudinally of the pipes. Spacers 25 have flange-like projections 26 located at their bottom edges, which projections rest upon the flanges 22 of the supports 20 thereby spacing the spacers slightly off of the bottom plate 1 of the rack.

The number of supports will depend upon the desired dimensions of the compartments to be formed and upon the length of the rack. In Fig. 1 a few supports 20 are shown, and it will be understood that supports will be provided as required. As will be apparent, the distance between adjacent supports 20 will depend upon the length of the spacers 25 and the dimensions of the compartments or bins in the rack will likewise be so governed. By providing at the edges 2 and 3 of the rack a spacer 27 which is essentially just half of the spacer 25, the pipes in run 10 of the coil will be covered and the compartment 30 will be bounded by smooth planar metallic walls capable of efficiently transmitting heat from the produce to the refrigerating coils by conduction. Compartment 31 will be similarly bounded by adjacent supports 20 and adjacent spacers 25 and compartment 32 by the supports 20, the spacer 25 on the pipes in run 12 and the side spacer adjacent the front wall 2 of the rack.

At the ends 4 and 5 of the rack cross-connecting coils 14 and 15 are covered by suitable plates 30 which essentially consist of half the supports 20.

The compressor-condenser unit employed forms no part of the present invention as there are a number of such units available on the open market. As shown the compressor 35 is driven by a suitable motor 36, and draws refrigerant through the pipe 17 and forces it through pipe 37 into the condenser 38 where the refrigerant is liquefied and returned to the coil through pipe 16, there being suitable control valves interposed in the customary manner.

In certain instances, such as for example, to ripen fruit that is received too green for immediate sale, it may be advantageous to apply heat to the display rack. For such operation pipes 16, 17 and 37 are connected so that the coil in the rack becomes the condenser and the condenser 38 becomes the evaporator.

From the foregoing it will be apparent that the refrigerating apparatus of the present invention is capable of being installed in existing racks or in new racks of the same dimensions. The apparatus itself forms dividers that bound the individual compartments by smooth planar metallic walls through which heat may be conducted efficiently. The refrigerating apparatus does not in any way interfere with the manner in which the merchandise is displayed both directly and through images reflected by the mirror. The refrigerating apparatus can be built economically without sacrificing quality and can be maintained in clean, sanitary condition without difficulty.

While I have chosen to show my invention by illustrating and describing a preferred embodiment of it, I have done so by way of example only as there are many modifications and adaptations which can be made by one skilled in the art within the teachings of the invention.

Having thus complied with the statutes and shown and described a preferred embodiment of the invention, what I consider new and desire to have protected by Letters Patent is pointed out in the appended claims.

What is claimed is:

1. In a refrigerated display rack of the open

type; a refrigerating coil extending back and forth from end to end of the rack and having a plurality of layers disposed with sections of the coil in each layer aligned vertically with corresponding sections in the other layers; lateral partition members extending from side to side of the rack and containing perforations through which said coil extends; and longitudinal partition members engaging the vertically aligned sections of said coil and abutting against adjacent ones of said lateral partition members to space the latter members longitudinally of the coil and to divide the rack into individual open top compartments arranged in a plurality of rows that extend from end to end of the rack, with each row containing a plurality of compartments.

2. In a refrigerated display rack of the open type; a rectangular bottom plate; a plurality of planar perforated generally U-shaped metallic supports disposed on said plate in spaced apart upright position and extending from side to side thereof; metallic pipes extending from end to end of the rack and through the perforations in said supports at substantially right angles thereto, said supports holding the pipes in spaced apart vertical rows extending from end to end of the rack; end pipes connecting said pipes together to form a continuous coil through which a heat exchange medium may be passed; and metallic separators each engaging the pipes in a section of a row and abutted against adjacent ones of said supports and forming with the supports, walls dividing the rack into a plurality of individual open top compartments.

3. In a refrigerated display rack of the open type; a rectangular bottom plate member; a refrigerating coil disposed above said bottom member and extending back and forth from end to end thereof, said coil having a plurality of layers disposed with sections of each layer aligned vertically with corresponding sections of the other layers; a plurality of lateral partition members extending from side to side of the rack each containing perforations through which the coil sections extend to permit movement of the member longitudinally of the rack and coil; and a plurality of longitudinal partition members engaging the vertically aligned sections of said coil and abutting against adjacent ones of said lateral partition members to position the latter members longitudinally of the coil and to divide the rack into individual open top compartments.

4. In a display rack of the open type; a bottom plate; a plurality of supporting members of generally U-section disposed in parallel spaced apart relation on said plate and extending from edge to edge thereof, said members each containing a plurality of perforations arranged in spaced apart vertically disposed rows with a plurality of perforations in each row, and with the rows and perforations therein in each member aligned with a corresponding row and perforation in the other members; a heat exchanger coil threaded

through said perforations and extending from edge to edge of the plate and forming a plurality of spaced apart vertically aligned coil sections; and a separator of generally U-shaped section fitted over each coil section and abutting adjacent ones of said supporting members to form with said supporting members a plurality of individual open top compartments in said rack.

5. A refrigerating unit adapted for use in an existing display rack having a bottom plate and side walls extending upwardly therefrom around the periphery thereof comprising: generally U-shaped supports disposed in parallel relation upon said plate and extending between opposite ones of said side walls, said supports being perforated; a heat exchange coil extending through the perforations in said supports and supported thereby in a plurality of parallel vertically disposed sections each extending between the other 10 opposite ones of said side walls with a section along the inner face of each of the first said opposite side walls; metallic cover plates for said coil sections abutted against adjacent ones of said supports and extending therebetween; and metallic end cover plates disposed alongside the inside 15 faces of said other opposite ones of said side walls, said supports, cover plates, and end cover plates dividing said rack into a plurality of independent open top bins, each of which is bounded by walls through which heat may pass by conduction.

6. In a refrigerated display rack of the open type; a rectangular bottom plate member; a refrigerating coil disposed above said bottom member and having a plurality of spaced apart sections extending from end to end of said member, each section containing a plurality of pipes disposed in vertical alignment; a plurality of lateral partition members each having a plurality of 20 perforations arranged in spaced apart vertical rows through which perforations said coil projects; feet on said lateral members engaging said plate member to support the partition member thereon thereby to support the coil above said bottom member, said partition members being 25 movable on said bottom plate longitudinally of said rack and pipes; and a plurality of generally U-shaped members each engaging both sides of the vertically disposed pipes in a coil section and abutting against adjacent ones of said lateral 30 partition members to fix those members longitudinally of the rack and pipes and with the lateral members to divide the rack into a plurality of individual open top compartments.
